G. C. VENNUM

WATER HEATER

Filed July 29, 1921

UNITED STATES PATENT OFFICE.

GEORGE CARL VENNUM, OF WESTFIELD, NEW JERSEY, ASSIGNOR TO EDGE MOOR IRON COMPANY, OF EDGE MOOR, DELAWARE, A CORPORATION OF DELAWARE.

WATER HEATER.

Application filed July 29, 1921. Serial No. 488,455.

My invention relates to steam boilers or to that portion of a water heating system used for preheating water. The object of my invention is, in the first place, to provide for efficient construction involving water tubes and steam soot blowers which will, in a construction in which the water tubes are situated close together, provide an ample and convenient space for the soot blowing nozzles. Another object which I have in view is to provide a construction which will enable me to build up a heater section formed of divisional header ends and in which it is made practicable to diminish the size of the header ends over that commonly necessary by using, in combination with the header ends, water tubes having contracted ends. In this way I make it practicable to use large diameter tubes and to space them in the gas pass so as to obtain a high ratio of tube surface to the gas pass area, an important feature of construction in view of the high pressures now coming into use. Still another object of my invention is to provide a construction in which the headers are made up of cylindrical header ends nested together in a highly convenient and practical manner.

The nature of my improvements will be best understood as described in connection with the drawings in which they are illustrated and in which—

Figure 1 is a partly sectional plan view of a water heater embodying my invention, and

Figure 2 is a side elevation partly in section and with parts broken away of the water heater shown in Fig. 1.

2 and 4 are respectively the upper and lower headers of my improved water heater, as shown, and preferably made up of sectional units 6—6 which, as illustrated, are each of cylindrical form nested together, as shown in Fig. 1, so that the alternate rows are staggered with respect to each other. As shown, each row of cylindrical units is fastened together alternately by rivets, as indicated at 12, and by nipples, as indicated at 14, and the ends of the rows are connected by nipples, as indicated at 16, 18 and 20 so as to provide a sinuous path through the heater when the headers are connected by water tubes 8, the ends of which are contracted, as shown in Fig. 2, for the double purpose of providing spaces, indicated at 10,

for the insertion of soot blowing steam nozzles 40, provided, as is shown, with discharge nipples 42. The nozzles, as shown, are connected with a steam supply pipe indicated at 44. Another useful function, involved in the use of the water tubes with contacted ends, is that it enables me to construct and use header ends of smaller size than has heretofore been customary and necessary owing to the fact that the tube holes provided in the header ends can be and are made smaller, thus providing for a wall of sufficient strength in a header end of less than usual standard size. The headers are, of course, provided with the usual hand holes which are closed by covers of any convenient construction. Conveniently, the heater section, made up, as shown, of four rows of header ends, is enclosed in a frame made up of plates 32 and 38.

24 indicates the water supply pipe connected by an inlet branch 22 with the first header section, and 26 is a branch pipe connecting the rear header section with the water supply pipe; each branch pipe is provided with a valve indicated at 28, and a valve, indicated at 30, is located in the water supply pipe between its connection with the branch pipes. When the section is in operation, the valve 30 will, of course, be closed and the valves 28 open, and by closing the valve 28 and by opening the valve 30 the header section can be cut out.

Having now described my invention, what I claim as new and desire to secure by Letters Patent, is:

1. A steam boiler having in combination headers, spaced water tubes connecting said headers having contracted ends whereby enlarged spaces between the tubes are formed adjacent to the headers and steam soot blowing nozzles extending through said enlarged spaces.

2. A steam boiler having headers made up of cylindrical units nested together so that alternate rows will be staggered, in combination with water tubes connecting opposite units of the headers nipple connections connecting adjacent header units in pairs to provide for the desired circulation in the boiler and rivets securing adjacent interconnected headers together.

GEORGE CARL VENNUM.
